UNITED STATES PATENT OFFICE.

DOUGLAS BREWS, OF CLEVELAND, OHIO.

BLOW-OUT DEVICE FOR STEAM-BOILERS.

No. 881,895.

Specification of Letters Patent. Patented March 17, 1908.

Application filed November 11, 1907. Serial No. 401,576.

To all whom it may concern:

Be it known that I, DOUGLAS BREWS, a citizen of the United States, residing at Cleveland, in the county of Cuyahoga and 5 State of Ohio, have invented certain new and useful Improvements in Blow-Out Devices for Steam-Boilers, and do declare that the following is a full, clear, and exact description of the invention, which will enable 10 others skilled in the art to which it appertains to make and use the same.

My invention relates to blow-out devices for steam boilers, and the invention consists in a device adapted to be moved up and 15 down at the front of a boiler so as to reach the flues therein successively and to cleanse the same by blowing steam under boiler pressure through the flues, all substantially as shown and described and particularly 20 pointed out in the claims.

In the accompanying drawings, Figure 1 is a front elevation of a boiler equipped with my invention, and Fig. 2 is a vertical sectional elevation of the front portion of the 25 said boiler and its equipments.

The device as thus shown comprises a boiler, B, say for marine purposes, though not necessarily limited to such purpose or use, and which is provided with three several 30 sets or series of tubes indicated for convenience of reference by 2, 3 and 4, respectively, and running in parallel rows vertically and transversely. The central or middle series, 2, extend down below the two side series of 35 tubes in this instance relatively as shown, and the said two side series 3 and 4 correspond with each other in location and arrangement. The said tubes severally are of the usual boiler kind and have no novelty in 40 themselves, and C represents a breeching or walled inclosure arranged at the front of the boiler and provided with tubes 5 through which the products of combustion pass from the furnace. Said tubes 5 extend through 45 the air heating chamber c, which is closed off from the exhaust by diaphragms or plates 7 and 8 supporting said draft tubes 5.

Each series of boiler flues, 2, 3 and 4, respectively, is provided with its own blow-out 50 or cleansing device; and these are alike. Thus, the device in each case has a steam supply and supporting tube D projecting through said breeching C from the top downward and having a bearing in bracket 9 55 thereon and in one of the said exhaust tubes 5 through which it extends into the space be-

neath the same, more or less as the service demands, said pipe D being slidable or adjustable up and down in these bearings to reach the boiler flues at all elevations. 60

A tubular cross head G is fixed at its middle to each pipe D and carries injector nipples d corresponding to the rows of boiler tubes, thus reaching all said tubes in each section as the cross head for each is moved 65 over the same upwards or downwards or both, and stopped for the time opposite said tubes. Now, this leads up to the vital and material difference herein over other inventions in this art familiar to me, and differentiates the same from other constructions in this, that I provide a set of stay bars, rods or braces E for each cross-head behind the same, and which rods or braces are fixed in an upright position within casing C opposite 70 the flue area of the boiler and at least equal in length to the movement of the cross-heads in front of said flues. These braces are material and important for two reasons, viz., to overcome the back pressure by the steam as 75 it is blown out through nipples d in the cross-head and to keep the cross head from turning or rotating more from working position at either end in or through pipe D, said pipe 80 really being free to turn within limits in its bearings and having no other means for keeping it and the cross-head square with the boiler tubes but these back braces or guides. It will be seen that said braces are arranged 85 behind the respective ends of the cross-heads, thus preventing possible turning on the axis of pipe D, and that they form a back-ing along which the cross-heads slide but are 90 otherwise independent thereof.

The general steam supply pipe H has the 95 several distributing pipes D connected therewith by sections P and elbow or equivalent joints J here and there, which permits said pipes or connections to flex or bend more or less according to the positions of pipes D, 100 and as clearly disclosed in the two positions of corresponding pipes in Fig. 2, the straight connection showing position when the cross-head is down, say as at middle section of tubes, Fig. 1, and the flexed or bent position 105 as when the cross-head is raised, seen at the left in Fig. 1. Handles L serve to operate the parts by hand, but this might be done by power connections. Experience shows that the said vertical bearing rods E for the 110 cross-heads need to be especially strong and firm, because in my earlier experiences with

them I found some that had been bent by the back pressure of the steam which greatly crippled operations. Hence, such bars or rods need to be strong enough to resist such pressure, say approximately two inches across if round rods be used.

If the draft tubes be not used in a boiler setting any sufficient bearing for pipes D which is the equivalent of tubes 5 may be 10 substituted.

What I claim is:—

1. A boiler having a series of flues arranged in parallel rows vertically and horizontally, a steam supply pipe and a cross-head fixed to said pipe at its middle and provided with a series of jets at the front of said flues respectively and fixed upright supports behind the ends of said cross-head adapted to back the same against back pressure by the discharging steam.

2. A tubular boiler, a steam supply pipe having a steam delivering cross-head adapted to be raised and lowered opposite the front of the tubes of the boiler to different 25 horizontal planes, in combination with fixed

vertical braces at the ends of said cross-head in respect to which said head is slideable up and down to different elevations, and the said braces extending the full depth of the space over which said cross-head is 30 movable.

3. A steam blow-out device for boiler tubes comprising a vertical and centrally disposed steam supply pipe and a cross-head fixed at its middle on the lower end of said pipe and provided with a series of steam discharge nipples between its ends, in combination with fixed vertically disposed, braces immediately behind the ends of said cross-head extending the full depth of said 40 boiler tubes, whereby said cross-head is backed alike at all elevations and held in definite working relations to the flues of the boiler.

In testimony whereof I sign this specification in the presence of two witnesses.

DOUGLAS BREWS.
